Primary Examiner — Elizabeth J Oswecki(74) *Attorney, Agent, or Firm* — Cantor Colburn LLP(57) **CLAIM**

The ornamental design for automatic teller machine, as shown and described.

DESCRIPTION

FIG. 1 is a front perspective view of an automatic teller machine, showing my new design;

FIG. 2 is a front elevation view thereof;

FIG. 3 is a top plan view thereof;

FIG. 4 is a left side elevation view thereof;

FIG. 5 is a rear elevation view thereof;

FIG. 6 is a right side elevation view thereof; and,

FIG. 7 is a bottom plan view.

The portions of the automatic teller machine shown in broken lines form no part of the claimed design.
